UNITED STATES PATENT OFFICE.

MARK R. WOODWARD, OF WASHINGTON, DISTRICT OF COLUMBIA.

TUBE FORMING AND COATING MACHINE.

1,140,430.

Specification of Letters Patent.

Patented May 25, 1915.

Application filed April 17, 1908. Serial No. 427,592.

To all whom it may concern:

Be it known that I, MARK R. WOODWARD, a citizen of the United States, residing at Washington, in the District of Columbia, have invented a new and useful Tube Forming and Coating Machine, of which the following is a specification.

My invention relates to a machine for winding or forming a tube or tubes from strips of flexible material and for coating the formed tube on its inner and outer surfaces.

Heretofore it has been customary to either coat one or both surfaces of one or both of the strips before they were formed into a tube; or to cut the tube into sections or lengths and immerse the latter in the coating material, thus coating both surfaces thereof. The first method has been found to be unsatisfactory, while in the second the amount of coating placed on the sections could not be regulated, thus causing a great waste of the material.

It is the object of this invention to overcome the above objections by providing the former, on which the tube is formed, with means for applying a coating of proper thickness to the inner surface of the tube.

Another object of the invention is to combine with the tube forming mechanism means for applying a coating to the outer or exterior surface of the tube.

A further object of the invention is to regulate the supply of the coating material to one or both surfaces of the tube.

Referring to the drawings—Figure 1 is a plan view of a machine embodying my invention. Fig. 2 is a side elevation of the machine illustrated in Fig. 1, with parts of the tube forming mechanism removed therefrom. Fig. 3 is a longitudinal section of a portion of the former. Fig. 4 is a transverse section of the former on the line 4—4, Fig. 3. Figs. 5, 6 and 7 are views illustrating different forms of the interior coating means. Fig. 8 is a transverse section on the line 8—8, Fig. 5. Fig. 9 is a transverse section on the line 9—9, Fig. 1.

In the drawings, A indicates a suitable frame or bed, mounted upon legs a.

2 indicates a standard rising from the bed near one end thereof and adapted to support a tube former 3. The former 3 is preferably made hollow and may be held stationary in the standard or caused to rotate in suitable bearings therein.

4, 4, indicate the strips of flexible material arranged to be fed continuously from opposite sides of the former, and at an angle thereto.

4' indicates a glue receptacle mounted in close proximity to one of the strips of material, and 4'' indicates a roller or wiper adapted to apply glue or paste to one surface of the strip for uniting it to the other strip as they are formed into tube shape on the former.

The means for forming or winding the tube upon the former may consist of any suitable or preferred mechanism. I have shown one suitable form of mechanism, in which 5 indicates an endless belt for spirally winding the strips on the former continuously. The belt 5 is coiled around the former and is also carried around pulleys 6, 6, mounted on vertical shafts 7, 7, on opposite sides of the former, whereby the belt may be driven. One of the vertical shafts is provided with suitable gears meshing with gears (not shown) carried by a driven shaft 8, extending longitudinally of the bed A.

9 indicates a stepped pulley keyed to a shaft 10. This shaft has a spur gear 10' adapted to drive a counter shaft 11 by means of a gear 11'. From the shaft 11, motion is communicated to the main driving shaft 12 through the pinion 12', gears 13, 13, (one of which is loosely mounted on the shaft 10), and intermediate pinion 13'.

14 indicates a rod connected at its opposite ends by universal joints to the main driving shaft and the shaft 8.

If desired, both pulleys 6, 6, may be positively driven. In such case, the pulley on that side of the former opposite to the shaft 8 is geared to a cross shaft 8', which is driven by suitable gearing from the shaft 8.

While I have described but one winding belt and belt driving mechanism, it will be understood that the machine may be provided with more than one belt and belt driving mechanism, as may be desired (see Fig. 1).

Combined with the tube forming mechanism are means for applying a coat of material, such as a waterproofing material, to the inner surface of the tube after the two strips of flexible material have been formed into tube shape. These coating means are mounted on or formed in the surface of the

former 3, at some suitable distance beyond the tube forming means, as shown in Fig. 1, and comprise a channel or opening 15, of suitable length, over which the tube passes as it moves toward the free end of the former. By conducting to the channel a supply of the coating material, the formed tube, which fits closely to the former, receives an application of the material over its entire inner surface.

The source of supply for the material is indicated at 17. It may consist of a reservoir preferably having a suitable heater 18, for heating the material to any desired degree. Connected to the reservoir is a pipe 19 which connects with a conduit 20 that is carried through the shaft 10 and its bearings into the former, where it extends to and is connected with the channel 15, to conduct the material thereto. If desired, an auxiliary or storage chamber 15' may be interposed between the channel 15 and the inner end of the conduit 20.

In order that the supply of coating material from the reservoir 17 to the channel 15 may be regulated, I provide a valve 21 in one of the pipes. It will be understood that the amount of material applied may also be regulated by raising or lowering its temperature; but that the valve serves to regulate the supply under any conditions of heat to which the material may be subjected.

Under some conditions it is desirable to heat the former. For this purpose I provide a heater, indicated at 22, preferably mounted within the former between the coat-applying means and its free end. It consists of an electric resistance, the conductor wires for which are carried through the former, as shown at 23. Any other form of heater may be used according to conditions and circumstances.

In Fig. 5 I have shown a different form of the invention. In this figure the coat-applying means comprises a channel 15^a formed in the outer surface of the former 3. 21', 21'' indicate a plurality of conduits leading to the channel 15^a, whereby it may be properly supplied with the material throughout its entire length.

In the forms of tube winding mechanism already described, it will be understood that the former is held stationary, while the tube revolves thereon and is fed continuously toward its free end, such movements of the tube being caused by the winding mechanism. During these movements of the tube every portion of its inner surface passes over the coat-applying means and receives an application of the material. As a result of this operation, the mandrel is lubricated, the waterproofing material is rubbed into the pores of the strips forming the tube and the crevices between the edges of the strips filled.

In Fig. 6 I have shown a former adapted for use in a tube winding mechanism wherein it is caused to rotate. In this form of mechanism it will be understood that the tube revolves with the former, but moves longitudinally thereof toward its free end. For this reason the coat-applying means extends circumferentially around the former, as shown at 15^b, so that the entire inner surface of the tube is coated. If desired, the former may be provided with a chamber 15^c and a feed channel 15^d between the conduit 20 and the coat-applying channel 15^b.

Fig. 7 illustrates a polygonally shaped former, indicated by the reference numeral 3'', adapted for making polygonally shaped tubes. The former 3'' is provided with a circumferential coat-applying channel 15^e. 20', 20'', indicate conduits leading to the coat-applying channel for supplying the material thereto.

When it is desirable to apply a coating of some material to the exterior surface of the tube, I combine with the tube forming mechanism suitable coat-applying devices, that are mounted on the machine bed, separate from the interior coat-applying means. These devices consist of a receptacle 26, preferably arranged below the former, and, when so arranged, its top plate is provided with a channel 26', in communication with the said receptacle, whereby the coating material may be brought into contact with and be applied to the outer surface of the tube. The channel 26' is preferably longer than the width of the strips of which the tube is formed. The top of the receptacle that engages with the tube is preferably concaved to conform to the general shape of the tube and assists in spreading the material thereon.

The receptacle 26 is mounted on a base 27 through which a feed pipe, secured to the receptacle, extends. Between the pipe and the base is a packing and a gland 27', which screw threads into the base 27. The gland 27' is provided with a sleeve 29 over which fits an adjustable plate 30. This plate is movable up or down on the sleeve 115 and may be secured in any position by a set screw 29'. The receptacle is preferably yieldingly supported in order that the coat-applying devices may readily adapt themselves to any irregularities in the tube or to tubes formed of different thicknesses of material or tubes formed of one or more strips of material. For this purpose, the receptacle 26 rests on a plate 31 between which and the plate 30 are provided springs 31'.

29^a indicates a conduit for supplying the coating material to the exterior coating devices. This conduit is connected with a chamber 32, into which the pipe 28 telescopes, at one end and at its opposite end 130

with the reservoir 17. A valve 32' controls the supply of material through the conduit 29^a.

33 indicates a branch pipe that may lead 5 to a reservoir containing a coating material different from that contained in the reservoir 17 and 33' indicates a suitable valve in such branch pipe.

By properly operating the valves 32' and 10 33', a coating material may be applied to one surface of the tube and a different coating material applied to its other surface; or only one surface coated as may be desired. When only the inner surface of the 15 tube is to be coated, the exterior coat-applying devices may be moved out of engaging position by adjusting the plate 30, or they may be entirely removed from the machine bed.

20 It will be understood that my invention is not limited to the forms of construction chosen for illustrative purposes herein, but that it may be embodied in other forms of construction, without departing from its 25 spirit, by those skilled in the art to which the invention relates.

What I claim is:

1. In a machine of the character described, the combination of a former, means 30 for forming a tube thereon and feeding it along the former, the said former being formed with a channel or opening in its surface, and means for supplying a suitable material to said channel.

35 2. In a machine of the character described, the combination of a former, means for forming a tube thereon and feeding it along the former, the said former being formed with an elongated channel in its surface, 40 means for supplying a suitable material to said channel, and a valve for regulating the amount of material delivered to said channel.

45 3. The combination of a mandrel having an elongated material holding channel in its peripheral surface, means for continuously forming a tube on the mandrel and feeding it therealong, a reservoir, and connections between the reservoir and the channel 50 formed in the mandrel for supplying the material thereto.

55 4. The combination of a mandrel having an elongated material holding channel in its peripheral surface, means for continuously forming a tube on the mandrel and feeding it therealong, a reservoir, connections between the reservoir and the channel formed in the mandrel for supplying the material thereto, and means for heating the mandrel.

60 5. In a machine of the character described, the combination of a mandrel having a channel formed in its surface between its opposite ends, adapted to hold a coating material, means for forming a tube on the mandrel and feeding it therealong and relative to the

channel formed in the mandrel, whereby the internal surface of the tube will receive an application of the coating material, a reservoir and connections between the reservoir and the channel for supplying material 70 thereto.

6. In a machine of the character described, the combination of a mandrel having a channel formed in its surface between its opposite ends, adapted to hold a coating material, 75 and means for forming a tube on the mandrel and feeding it therealong and relative to the channel formed in the mandrel, whereby the internal surface of the tube will receive an application of the coating material. 80

7. In a machine of the character described, the combination of a former, means for spirally winding a tube on the former and for moving it longitudinally and circumferentially simultaneously relative thereto, 85 the said former being formed with an elongated channel in its surface, a reservoir for a coating material, and connections leading through the former for supplying coating material from the reservoir to the said channel, whereby as the tube moves longitudinally and circumferentially of the former it receives a coating of the material from said channel. 90

8. In a machine of the character described, 95 the combination of a tube forming mechanism, means operating after the formation of a tube by the tube forming mechanism for coating the interior surface of the tube, and separate means for coating the exterior 100 surface thereof.

9. In a machine of the character described, the combination of tube forming means comprising a former provided with means for applying a coat of material to the interior 105 surface of the tube and means for feeding a strip of flexible material to the former, means, leading through the former, for supplying the coating material to the interior coat-applying means, and separate means 110 for applying a coat to the exterior surface of the tube.

10. In a machine for coating tubes, the combination of a former, means for moving a formed tube along the former, a coat-applying device provided with a channel arranged to engage with the exterior surface of the tube, means for supplying a coating material to the channel in the said coat-applying device, and means for yieldingly 120 supporting the coat-applying device in engagement with the tube.

11. In a machine of the character described, the combination of tube forming means, means for coating the interior surface 125 of the tube after the formation thereof, separate means for coating the exterior surface of the tube, and means for heating the former.

12. In a machine of the character de- 130

scribed, the combination of tube forming means, means for coating the interior surface of the tube after the formation thereof, separate means for coating the exterior surface of the tube, and means, interposed between the interior and exterior coating means, for heating the former.

13. The combination of a former, means for forming a tube thereon, means for coating the interior surface of the tube, separate means for coating the exterior surface of the tube, and means for adjusting the exterior coating means relative to the tube.

14. The combination of a former, means for forming a tube thereon, means for applying a coating to the interior surface of the tube, coat-applying devices for applying a coating to the exterior surface of the tube, and means for yieldingly supporting the exterior coat-applying devices.

15. The combination of a former, means for forming a tube on the former and moving the formed tube longitudinally and circumferentially thereon, and means for applying a coating material to the tube, the said means comprising a material holding receptacle having a concaved wall arranged to engage the exterior surface of the formed tube, said concaved wall being formed with an opening through which the coating material passes from said receptacle whereby the entire exterior surface of the formed tube is coated, and means for supplying material to said receptacle.

16. The combination of a former, means for forming a tube thereon, and means for applying a coating material to the tube, the said means comprising a material holding receptacle having a concaved wall arranged to engage the exterior surface of the formed tube, said concaved wall being formed with a centrally disposed elongated opening extending longitudinally of the former and permitting the material to flow from the receptacle for application on the tube, and means for supplying material to said receptacle.

17. In a tube forming and coating machine, the combination of a former formed with an elongated material holding channel extending circumferentially around the former, a reservoir, connections between the reservoir and the said channel or receptacle for supplying material thereto, and means for forming a tube on the former and moving it longitudinally thereof and past the said channel, whereby the tube receives a coating of the material contained in the channel upon its inner surface by the operation of moving over it.

18. In a tube forming and coating machine, the combination of a former formed with an elongated channel extending circumferentially and also longitudinally of the former, a reservoir, connections between

the reservoir and the said channel for supplying material thereto, and means for forming a tube on the former and moving it longitudinally thereof over the said channel, whereby the tube receives a coating of the material contained in the channel upon its inner surface by the operation of moving over it.

19. The combination of a former, means for forming a tube thereon, coat applying devices for applying a coating to the exterior surface of the tube after it is formed, the said devices including a plate formed with an elongated opening through which a coating material passes and arranged to engage the tube, whereby said tube is coated, and means for yieldingly supporting the said coat applying devices.

20. The combination of a former, means for forming a tube thereon, coat applying devices for applying a coating to the exterior surface of the tube after it is formed, the said devices including a plate formed with an elongated opening through which a coating material passes and arranged to engage the tube, whereby said tube is coated, means for yieldingly supporting the said coat applying devices, and means for adjusting the said coat applying devices.

21. The combination of a former, means for forming a tube thereon, means, including a concaved plate having an elongated channel formed therein and extending in a line parallel to the former and arranged to engage with the exterior surface of a tube for applying a coating thereto, and means for supplying coating material to the said coat applying means.

22. The combination of a former, means for forming a tube thereon, a coat applying device arranged to engage with the exterior surface of a tube formed on the said former and having a channel formed in its surface for holding a coating material, said channel being longer than the width of the strips of which the tube is formed, and means for supplying a coating material to the channel of said coat applying device.

23. The combination of a former, means for forming a tube thereon and moving it longitudinally of the former, a material holding receptacle having a tube engaging plate formed with an opening therein through which the material in the receptacle passes, connections with a source of supply for the material, a support for the said receptacle, and springs interposed between the receptacle and the support for yieldingly supporting the plate of the receptacle in engagement with the tube.

24. The combination of a former, means for forming a tube thereon and moving it longitudinally of the former, a material holding receptacle having a tube engaging plate formed with an opening therein

through which the material in the receptacle passes, telescoping connections with a source of supply for the material, a support for the said receptacle, and springs interposed 5 between the receptacle and the support for yieldingly supporting the plate of the receptacle in engagement with the tube.

25. The combination with a hollow mandrel and a belt arranged to wind paper strips spirally about the mandrel to form continuous tubing, of a tank for liquid coating, a conduit leading from the tank into the mandrel and opening outward through a slot longer than the width of the stock 15 strip and located in the surface upon which the strip slips, whereby the entire inner surface of the winding strip receives a uniform amount of liquid coating.

26. The combination of a mandrel formed 20 with a slot or groove in its outer surface, means arranged to wind paper strips spirally about the mandrel to form continuous tubing, a tank for liquid coating, and a conduit leading from the tank into and 25 through the mandrel to the slot or groove, whereby the entire inner surface of the strips receives a uniform coating of the liquid.

27. In tube making devices, the combination 30 with a mandrel adapted to receive a spirally wound paper strip, of means for supplying the entire inner surface of the

strip wound thereon with a coating material, and means whereby the coated surface of the wound strip is forcibly rubbed, transversely to the crevice between its turns, 35 whereby the tube is internally coated, the mandrel lubricated, the material worked into the surface of the paper, and the perfect filling of the crevice is assured.

28. The combination with a mandrel and 40 means for winding a paper strip thereon to form a tube, of a chamber within said mandrel for a liquid, means for supplying liquid to said chamber to coat the inner face of the tube, and means for controlling the supply 45 of liquid to said chamber.

29. The combination with a mandrel supported at one end and free at the other end, of means for winding a paper strip thereon to form a tube, a chamber for a liquid located 50 within said mandrel near the free end thereof, and a supply conduit for the liquid passing into the mandrel through the supported end thereof.

In testimony whereof I have hereunto 55 signed my name in the presence of two witnesses.

MARK R. WOODWARD.
